R. SCHMIDT.
STEAM PUMP.

No. 67,592.

Patented Aug. 6, 1867.

United States Patent Office.

RUDOLPH SCHMIDT, OF NEW YORK, N. Y.

Letters Patent No. 67,592, dated August 6, 1867.

IMPROVEMENT IN STEAM-PUMPS.

The Schedule referred to in these Letters Patent and making part of the same.

TO ALL WHOM IT MAY CONCERN:

Be it known that I, RUDOLPH SCHMIDT, of the city, county, and State of New York, have invented a new and improved Steam-Pump; and I do hereby declare that the following is a full, clear, and exact description thereof, which will enable others skilled in the art to make and use the same, reference being had to the accompanying drawings, forming part of this specification.

This invention relates to the device by which a pump for raising water is combined with and operated by a steam engine; and it consists in the arrangement of pistons of different sizes upon the rod sliding in the steam-chest, the vertical rod provided with collars and operated from the piston of the cylinder, whereby the ports for the admission and exhaust of steam are opened and closed; and in the arrangement of the stuffing-box, whereby the cylinders are separated.

Figure 1 represents a vertical section of the steam-pump through the line *z z* of fig. 2.

Figure 2 is a horizontal section of fig. 1, through the line *y y*.

Figure 3 is a vertical section of fig. 2, through the line *z z*.

Similar letters of reference indicate like parts.

A represents the steam-cylinder; B the water or pump-cylinder. C is the steam-piston, and D the pump-plunger. E is the piston and plunger-rod. F is the stuffing-box around the plunger D. *a a'* are water-valves which regulate the admission and discharge of the water. The piston C is driven in the ordinary way, by taking steam in the ends of the cylinder alternately, and the piston-rod being attached to the plunger, it will be seen that the plunger has the same stroke as the piston. When the plunger is driven down the valve *a'* will rise for the water to pass through, and when the plunger is drawn up the valve *a* will rise for the water to enter. The stuffing-box F is screwed into the chamber around the plunger, as seen in the drawing, and it will be noticed that there are two small holes or recesses in the top of it. On the bottom of the piston C there are two pins, which will fit into the holes when the piston is down, thus locking the stuffing-box and piston together. On the bottom of the plunger there is a square at *c*. The bottom of the plunger-cylinder, marked *d*, is movable, so that by taking it off a key-wrench may be put upon the square *c*, by which the plunger and piston may be turned round, and in this way the stuffing-box is screwed down when it requires tightening. The same thing can be done by turning the piston-rod. The stuffing-box can be taken out or put in place at any time by taking off the cylinder-head and removing the rod with the piston and plunger. The device by which the steam is admitted to and exhausted from the steam-cylinder is peculiar in its construction, as seen in figs. 2 and 3. As seen in fig. 1, steam is entering the bottom of the cylinder under the piston, through an aperture made through the head and the shell of the cylinder, which is seen in dotted lines, and is indicated by the arrow. From the top of the cylinder the steam is exhausting through the cylinder-head, as indicated by the arrow. The steam-chest is marked G, and it is attached directly to the cylinder-head of the engine. It is cylindrical in shape, and without valves, but with a rod which has three pistons attached to it, which slide in the chest, covering and uncovering the steam-ports or apertures so that the steam is admitted to and exhausted from the cylinder, according to the movement of the pistons in the chest. These pistons are marked *e e'* and *e'*. It will be noticed that the diameter of the pistons *e e'* is greater than that of *e'*. These pistons, with the rod, are moved back and forth in the chest by the pressure of the steam. *h*, fig. 1, is a vertical rod, which has collars on its upper portion marked *i i*. This rod is raised and lowered by a forked arm, marked *f*, which is attached to the piston-rod marked E, and moves up and down with it. It is attached to the piston-rod by a ring marked J. On the lower end of the rod *h* there is a piston-valve, *m*, which opens and closes an aperture, (seen in the drawing,) which passes from the chamber *n*, in which the piston *m* moves, to the steam-chest G. This aperture is seen in dotted lines in fig. 2. This chamber *n* is also connected with the end of the steam-chest, as seen in the same figure. When the piston-rod E rises, the rod *h* is raised, which allows the steam to exhaust from the upper end of the cylinder, by admitting steam into the end of the steam-chest behind the outer piston *e*, which drives the pistons to the other end of the steam-chest thereby opening the exhaust-port *k*, from whence the steam escapes, as seen in the drawing. The steam being admitted into the steam-chest always between the middle piston *e* and the small piston *e'*, the piston-valves are driven back, when the rod *h* descends, and the communication with the steam-chest and the chamber *n* is cut off and the exhaust-port opened. The difference in the areas of the pistons

e and *e'* effects this, for were there no difference the pressure would be balanced and the pistons would stand still. When they are thus thrown back the steam is exhausted from the bottom end of the cylinder through another aperture seen in the drawing at *g*, the exhaust pipe being attached at *p*.

I am aware that the apertures for the admission and discharge of water in water engines have been opened and closed by sliding piston-valves before, but I am not aware that such piston-valves have heretofore been moved by the pressure of steam operating upon such pistons when the movement depended upon a difference in the areas of such pistons. I am also aware that the plunger may be packed by rings or by other means equivalent to the stuffing-box, but I deem the stuffing-box substantially as shown the best method.

What I claim as new, and desire to secure by Letters Patent, is—

1. The arrangement of the pistons *e e'* and small piston *e'* upon the rod sliding in the steam-chest *G*, the vertical rod *h*, with collars *i i'*, operated from the piston *D*, substantially as herein shown and described, whereby the ports for the admission and exhaust of steam are opened and closed as and for the purpose specified.
2. The arrangement of the stuffing-box *F*, whereby the two cylinders are separated, substantially as shown and described.

R. SCHMIDT.
